UNITED STATES PATENT OFFICE.

WILLIAM NEIL, OF CHICAGO, ILLINOIS, ASSIGNOR TO WILLIAM NEIL & COMPANY, OF CHICAGO, ILLINOIS.

CONTAINER.

Application filed April 25, 1923. Serial No. 634,462.

The invention relates to containers and particularly to that type of these devices which are applicable for use in dispensing various commodities or the same commodity 5 from several individual receptacles which are removably arranged in the container.

The invention has as its prime object the provision of a container such as that above referred to which is provided with one or 10 more closures, the construction thereof and their connection with the container permitting them to cooperate with the receptacles and provide a means for effectively preventing dirt, dust and other foreign matter from 15 finding their way to the interior of the receptacles.

The invention is particularly applicable for use at automobile filling stations where small quantities of lubricating oils are dispensed from individual receptacles which 20 are refilled when empty. These receptacles are ordinarily provided with spouts which facilitate the introduction of the oil to the crank case or other portion of the machine, 25 and as at present these spouts are left uncovered, the invention is designed to provide a construction in which the closures will permit the introduction and removal of receptacles having the above structure into 30 the container and in which the spouts will be effectively closed when said receptacles are arranged in the container.

It is an object to provide a portable container with an arrangement which will accomplish the above enumerated objects and 35 in addition to provide a construction in which the closures may be held in an elevated position, which will thus facilitate the introduction and removal of a number of 40 said receptacles to and from the container.

It is an additional feature to provide the container with a bail or handle whereby the container may be transported from one location to another and to attach various elements employed in the structure including 45 the closures for the receptacles to this bail or handle.

It is a further object to construct the caps which, in the present instance provide the 50 closures, so that they will cooperate with the receptacles and facilitate the cooperation of the closures and the receptacles to insure the capping or closing of the receptacles.

The invention will be explained in detail 55 and more readily understood when read in

conjunction with the accompanying drawings which illustrate various arrangements which may be resorted to, it being therefore obvious that the invention is susceptible of modifications without departing from the 60 spirit of the appended claims forming a part hereof.

In the drawings Figure 1 is a plan view of a container constructed according to one embodiment of the invention.

Figure 2 is a section taken on line 2—2 of Figure 1.

Figure 3 illustrates a modified structure which may be employed in the structure.

The structure illustrated in the drawings 70 contemplates the use of a container 10 which is of a dimension sufficient to accommodate a number of receptacles 21 which are permitted to be removably arranged in the container 10. The container 10 is subdivided 75 into a number of separate spaces 11 by the bar 12 which extends lengthwise of the container and the plurality bars 13 which are arranged transversely thereto resulting in the provision of a separate compartment for 80 each of the containers.

A frame 14 is attached to the container 10 and provides a support for various elements of the structure and in addition provides a bail or handle whereby the structure 85 may be conveniently transported from one location to another.

In the present structure a bracket 15 is secured to the frame 14 and supports the rods 16 and 17 which are disposed upon opposite sides of the frame and extend from one end of the frame to the other. These rods and the bracket cooperate to provide a convenient means upon which to mount and retain the several pivoted elements 18 90 in their proper relative relation throughout the length of the frame. The pivoted elements 18 are disposed upon opposite sides of the frame, the elements of one side being arranged diametrically opposite those arranged upon the opposite side and extend outwardly from the frame to a point which substantially coincides with the centers of the subdivisions of the container 10 in which the receptacles are confined. These pivoted elements 18 are each provided with the inverted cup shaped elements 19 which are designed to engage the ends of the spouts 20 provided upon the receptacles 21 and provide a closure for the spouts when said 105 110

receptacles are arranged in the container. These elements 19 may be flared as illustrated or otherwise shaped to facilitate the removal of the receptacles from association therewith.

A means is provided for lifting and maintaining the pivoted elements 18 and the closures carried thereby in an elevated position which performs the additional function of 10 limiting the movement of the pivoted elements toward the receptacles. The means for performing these functions consist of the bars 22 and 23 which are arranged upon opposite sides of the frame and are pivoted 15 to the respective rods 16 and 17 carried by the bracket 15, they being respectively provided with the extensions 24 which engage the frame and limit the movement of said bars in a downward direction but permit 20 said bars to be moved upwardly. By virtue of the fact that these bars extend from one end of the frame to the other and are arranged below the pivoted members having the closures, and because of the further fact 25 that these bars are limited in their movement downwardly, said pivoted elements having the closures will be held in a substantially horizontal position upon opposite sides of the frame, but will be simultaneously lifted and held in a raised position by 30 said bars when the latter is moved from its normal position. This feature is of advantage because it permits all of said pivoted elements and their closures to be lifted and 35 held in an elevated position permitting the ready introduction of the receptacles into the container.

The arrangement permits one of the several pivoted elements and closures to be 40 lifted independently of the other which allows any one of the several receptacles to be introduced to or removed from the container without affecting the closure of another receptacle which will thus prevent foreign matter from finding its way into any of 45 the receptacles upon the removal or introduction of another of the receptacles to or from the container.

The structure may also include the bars 50 25-25 which are also disposed upon opposite sides of the frame and provide a means for centering the receptacles so that the ends of the spouts will align with the closures.

In the modified structure illustrated in 55 Figure 3 a vertically reciprocable closure is employed, which has the cone shaped center 26 and also the flared downwardly extending skirt portion 27. It is manifest that the structure of the center 26 will insure the 60 centering of the receptacle and the skirt will cooperate to prevent any foreign matter from lodging within or upon the rim of the spout.

From the foregoing explanations it is 65 manifest that a simple and effective struc-

ture is provided for preventing weather and foreign matter from finding its way into the interior of the receptacle and which permits the ready insertion and removal of a receptacle from the container. It is further evident that one receptacle may be placed or removed from the container without affecting the closures of the other receptacles and that all of said closures may be elevated when this is found necessary or desirable. 70 75

Having thus described the invention what I claim and desire to cover by Letters Patent is:

1. In a device of the character described, the combination of a container in which a receptacle is adapted to be removably arranged, a support, said support providing a handle for the container, a closure hinged to the support, a stop cooperating with the closure to limit the downward movement of the closure and to maintain said closure in a substantially horizontal position from which position said closure may be raised, said closure being provided to close the receptacle and to permit the removal of the receptacle 85 from the container. 90

2. In a device of the character described the combination of a container in which a receptacle is adapted to be removably arranged, a support, a gravity actuated closure secured to said support, said closure having means associated therewith for limiting the downward movement thereof and maintaining it in a normally horizontal position in which position said closure closes the receptacle, said closure being movable upwardly to permit the removal and insertion of a receptacle relative to the container. 100 105

3. In a device of the character described, the combination of a container, a support extending lengthwise of said container and being arranged substantially midway between the sides of said container to permit a receptacle to be arranged on either side of the support, a plurality of pivotally movable closures extending in substantially horizontal position in opposite directions from said support and cooperating with the receptacle to close the receptacle, said closures being removable from said horizontal position to permit the removal of the receptacle from the container, and means secured to the support for holding said closures in said substantially horizontal position. 110 115

4. In a device of the character described, the combination of a container, a support extending lengthwise of said container and being arranged substantially midway between the sides of said container to permit a receptacle to be arranged on either side of the support, a plurality of closures arranged upon opposite sides of said support and being gravity actuated to close the receptacles and movable to permit the removal of the receptacles from the container and means 120 125 130

for limiting the downward movement of said closures.

5. In a device of the character described, the combination of a container for receptacles, a support extending lengthwise of said container and being arranged substantially midway between the sides of said container, said support providing a handle for the container, a plurality of closures arranged upon opposite sides of said support and being operable to close said receptacles and to permit the removal of the receptacles from the container, and means for holding said closures in an elevated position, said 10 means providing a means for limiting the movement of said closures toward the receptacles.
6. In a device of the character described, the combination of a container, into which a plurality of receptacles may be removably arranged, a bail secured to said container, a plurality of members having caps which are provided to form closures for said receptacles, said members being pivotally connected to an element attached to the bail and said member having said caps being permitted to be moved to allow said receptacles to be arranged in and removed from the container.
- 20 7. In a device of the character described, the combination of a container into which a plurality of receptacles may be removably arranged, a bail secured to said container, a plurality of members pivotally secured for movement with respect to said bail and extending in opposite directions from said bail, said members being provided with caps which form closures for said receptacles, and means for limiting the movement of said pivotally secured members toward said receptacles, said means providing a means for moving said pivotally secured members away from said receptacles.
- 25 8. In a device of the character described, the combination of a container into which a plurality of receptacles may be removably arranged, a bail secured to said container, a plurality of members forming closures for the receptacles, said elements being independently movable to permit the introduction and removal of said receptacles and means for elevating all of said elements and holding same in elevated position.
- 30 9. In a device of the character described, the combination of a container into which a plurality of receptacles may be removably arranged, a bail secured to said container, a plurality of members pivotally secured for movement with relation to said bail and extending in opposite directions from said bail, said members being provided with caps which form closures for said receptacles, and means for limiting the movement of said pivotally secured members toward said receptacles, said means providing a means for moving said pivotally secured members away from said receptacles.
- 35

tending in opposite directions from said bail, said members being provided with caps which form closures for said receptacles, and means for limiting the downward movement of said pivotally secured members toward said receptacles and maintaining said closures in a substantially horizontal position.

40 45 50

55 60 65

In witness whereof, I hereunto subscribe my name this 23rd day of March A. D., 1923.

WILLIAM NEIL.
